UNITED STATES PATENT OFFICE.

JULIUS FREDERIK GEORG POUL HARTMANN, OF COPENHAGEN, DENMARK.

ELECTRIC JET WAVE COMMUTATOR AND INTERRUPTER.

Application filed March 17, 1926, Serial No. 95,210, and in Great Britain March 25, 1925.

This invention relates to apparatus in which a wave-shaped conductive liquid jet is used for effecting the closing or interruption of an electric circuit, and particularly to the so-called jet-wave commutators and interrupters which are described for instance in my U. S. patent specifications Nos. 1,306,335 and 1,365,491, and the main object of the invention is to provide an improved electrode or part of the same or arrangement of electrodes for use in such devices in order to increase the security of service and in some instances to reduce the electric resistances.

In accordance with the invention an electrode or electrode part coating with the conductive jet-wave is formed as one or more conductive walls arranged in the direction of propagation of the jet-wave liquid particles at said wall or walls, or nearly in that direction, and protruding laterally more or less into the jet-wave so as to touch the same without cutting the jet-wave or interfering materially with the normal advancing motion of the wave-figure thus making it possible to pass an electric current from the wall into said jet-wave.

The invention further comprises certain embodiments of electrodes and combinations of such which will appear from the following detailed description.

Referring now to the accompanying drawings:

Figures 1 and 2 are diagrammatic views of jet-wave commutators including certain embodiments of the invention.

Figures 3, 4 and 5 are a side view, a front view and a top view respectively of a so-called wing electrode constituting an embodiment of the invention,

Figures 6, 7 and 8 are similar views of a double wing electrode or twin wing electrode.

Figures 9 and 10 are diagrammatic views of jet-wave commutators provided with wing comb electrodes and so-called multi-rib electrodes respectively,

Figures 11 and 12 are a front view and a top view respectively of a double multirib rod electrode,

Figure 13 is a diagrammatic view of a jet-wave commutator including certain embodiments of the invention,

Figures 14 and 15 are a front view and a

top view respectively of a multirib rod side electrode,

Figure 16 is a diagrammatic view of a jet-wave commutator including certain embodiments of the invention,

Figure 17 is an enlarged top view of one of the electrode sets shown in Figure 16, and Figure 18 shows a further embodiment.

In all of those figures which show a jet-wave commutator the letter J designates a jet-wave, preferably of mercury, which issues from a nozzle N, passes a magnetic field F, is in constant contact with an electrode E and co-acts with several other electrodes. T is the secondary of a transformer delivering the current which in co-action with the field F produces the waves on the jet.

The improvements more particularly described in the following mainly relate to the various electrodes of such a jet-wave-commutator but may also be used in several other apparatus in which a jet-wave conductor is used for the closing or interruption of an electric circuit. The general principle can best be explained in connection with the auxiliary electrode for conducting the rectified current outwards from the commutator.

Figure 1 shows a commutator with such an auxiliary electrode E' of improved type. The electrode E' consists of a wing of conductive material arranged in the direction of the movement of the jet-wave liquid-particles at said wing and generally but not always perpendicularly to the plane of the jet-wave. The wing is furthermore adjusted in such a position that the jet-wave during its movement slides down along the edge of said wing without being cut or damaged by the same, the jet-wave being in constant touch with this wing. If the wing is arranged in the plane of symmetry of the commutator, i. e. in a plane perpendicular to the plane of the jet-wave and passing through the position of the jet when void of current as shown in Figure 1 and is sufficiently long, the jet-wave will always connect the wing with either the electrode part E₁ or the electrode part E₂.

In the position 1 of the jet-wave shown in full lines the electrodes E' and E₁ are connected through the part ab of the jet-wave and in the somewhat later position 2 shown in dotted lines the electrodes E' and E₂ are connected through the part cd. Obviously the condition for an uninterrupted

connection between the main-electrode E_1 , E_2 , and the auxiliary electrode E' is that the length of the latter is greater than half the wave length $\lambda/2$ of the jet-wave.

5 If the electrode E' is arranged in the plane of symmetry of the commutator as shown in Figure 1, knives w_1 and w_2 of conductive or insulating material must generally be placed on either side of the wing to interrupt, at the proper moment, the connection formed by the jet-waves between the electrode parts E_1 and E_2 , during the first phase of the commutation.

10 Instead of one single wing E' two or more wings arranged on opposite sides of the plane of symmetry of the commutator may be used. An electrode of this type with two wings E'_1 and E'_2 is shown in Figure 2. Here again each wing extends at least over one half-wave of the jet. The middle part of the commutator now being left free a single knife w may be positioned here to cut the jet-wave. The lower edges of the wings E'_1 and E'_2 must be placed at such a level that the jet-wave releases its hold on the edge nearest to that electrode side which the jet-wave is just leaving before the jet-wave is cut by the knife. Otherwise the commutation-spark will appear at said edge, thus in Figure 2 at the left instead of at the knife. In order to secure the interruption of the connection between the side of the electrode and the wing, at the proper moment, two knives w'_1 and w'_2 may be applied to cut the jet-wave between parts E'_1 and E_1 , and the parts E'_2 and E_2 , respectively.

15 The herein described auxiliary electrodes are mainly adjusted in the direction of the motion of the particles of which the jet-wave is built up, that is in, or nearly in, planes perpendicular to the plane of the jet-wave and radiating from the middlepoint of the field F .

A constructional embodiment of the wing proper is shown in Figure 3-5 inclusive. It consists of a steel strip C fixed to an arm A . The edge of the strip facing towards the jet-wave is sharpened. It has been found that the edge of the wing should not be exactly parallel to the plane of the jet-wave. The lower part of the wing preferably protrudes a little farther into the jet-wave than the uppermost part. The wing-electrode may advantageously be constructed as a twin-electrode, as shown in Figures 6-8. The jet-wave then travels down the slit between the two wings C_1 and C_2 . The width of the slit is slightly reduced in the direction of the movement of the jet-wave. As shown in Figure 8 each wing may be provided with two or more edges instead of having a single one, with the view of securing a more perfect contact between the jet-wave and the auxiliary electrode.

20 Two wings or two twin-wings may be placed on opposite sides of the plane of symmetry of the commutator, or a number of such

wings may be used, the wings being either separated or collected in a unit. In the latter case the commutator may assume the form shown in Figure 9. The two members E'_1 and E'_2 which are adapted to be short-circuited or which may be connected to one single electrode consist each of a comb of wings. The wings or teeth of the comb may have constant mutual distances. It should be noticed however that it very often will be considered advantageous to arrange the wings C_1 , C'_1 , C''_1 , . . . with mutual distances gradually decreasing outwards against the limit of the jet-wave and moreover with different inclinations in order to bring the single wings to coincide, more or less exactly with the direction of movement of the jet-wave particles in the considered point of the electrode. The latter may be built as a twin-electrode, each of the two parts E'_1 and E'_2 then consisting of two similar members facing each other. A practical embodiment of the electrodes E'_1 and E'_2 is illustrated in Figures 14 and 15. Each member of the twin-electrode has been made from a cylinder on which a series of sharp circular ribs has been produced by turning. After the production of the ribs the cylinder has been bent in circular form with a radius equal to the distance from the member to the middle point of the field whereby the result is obtained that the individual ribs are each adjusted in the direction of the motion of the particles of the jet-wave at the particular rib. The herein described electrode or electrode member having a multi-ribbed or corrugated surface is preferably called a currycomb-electrode. The two parts E'_1 and E'_2 shown in Figure 9 may be extended inwardly so as to meet and form one single electrode or twin-electrode. A twin-electrode of the indicated description and of the currycomb type is shown in Figures 11 and 12, while Figure 10 illustrates a complete commutator furnished with a currycomb-electrode E' .

25 It has been indicated above that the improvements not only apply to the auxiliary electrode E' Figure 1, through which the commutator current is conducted away from the commutator. The electrode E in Figure 1 which serves for the introduction of the auxiliary current into the jet-wave may also be made as a wing-electrode, or particularly and preferably as a curry-comb-electrode. Figure 10 also serves to illustrate this application of a curry-comb E .

30 The two parts E_1 , E_2 , Figure 1, of the main electrode may also be produced as wing-electrodes or particularly as curry-comb electrodes touching the jet-wave. In this way commutators with exceedingly small resistance may be built. In Figure 16 such a commutator is illustrated while in Figure 17 E_2 designates one of the electrode parts formed as a currycomb. Facing towards the part E_2

on the opposite side of the jet-wave a similar electrode E_2' is placed. At the side of the electrode E_1 a similar electrode E_1' is placed. The electrodes E_1 and E_2' are electrically connected with each other, and they have the same function as the auxiliary electrode E' shown in Figure 1. During the passing of the jet-wave between the electrodes E_2 and E_2' and between the electrodes E_1 and E_1' , the commutated or rectified current has only to travel from the part E_2 to the part E_2' or from the part E_1 to the part E_1' through the interjacent part of the wave, thus meeting an extremely small resistance only.

Figure 13 serves to illustrate an important application of the electrode principle under consideration. It has been found that a wing-electrode adjusted in the plane of symmetry of the commutator is very suitable for combination with other auxiliary-electrodes of various types. The advantage of such compound-electrodes or electrode-aggregates is mainly the increased reliability which they offer. The different components being short-circuited and the jet-wave simultaneously touching the various parts, more parallel ways are opened to the current. If one of these should by accident break down others are available, the possibility of an interruption of the circuit being thus very small. In Figure 13 the wing-electrode E' has been combined with two curry-comb-electrodes E_1' and E_2' . In Figure 16 the wing-electrode in the plane of symmetry of the commutator has been replaced by a so-called wedge-electrode. This wedge-electrode is of course electrically connected with the auxiliary electrode parts E_1 and E_2 .

In the embodiment of the invention shown in Figure 18 all of the electrodes E , E' , E_a , E_a' and E_b are twin electrodes, the two halves of each of which are arranged on opposite sides of the plane of the jet-wave. The auxiliary current is conducted into the jet through two curry-combs E , and the commutated current is conducted away from the commutator through two curry-combs E' , three twin wings E_a , E_b and E_a' and furthermore through two curry-combs E_a' and E_b' which are arranged adjacent and opposite to the two sides E_1 and E_2 of the main electrode respectively in a manner similar to that shown in Figure 16. The twin wing E_b' is arranged in the plane of symmetry of the commutator, and the twin wings E_a , E_a' are arranged symmetrically with respect to this plane.

Having thus full described my invention I claim as new and desire to secure by Letters Patent:

1. In an electric jet-wave apparatus the combination of means for producing a conductive liquid jet-wave, and an electrode member comprising a solid conductive wall

arranged substantially in the direction of propagation of the jet-wave liquid particles at said wall and protruding laterally to a certain extent into the jet-wave so as to touch the same without cutting the jet-wave and interfering materially with the normal advancing motion of the wave figure, thus making it possible to pass an electric current from the wall into said jet-wave at least for a short time.

2. The device of claim 1, in which the said conductive wall consists of a wing arranged in a plane perpendicular to the plane of the jet-wave and passing through the position of the jet when currentless with its edge constantly touching the jet-wave during its passage of the wall.

3. The device of claim 1, in which the said conductive wall consists of a wing arranged in a plane perpendicular to the plane of the jet-wave, the length of said wing being greater than the length of half a wave of the jet-wave at said wing.

4. In an electric jet-wave apparatus the combination of means for producing a conductive liquid jet-wave, and two electrode parts arranged symmetrically with respect to the position of the jet when currentless and each comprising a wing arranged in a plane perpendicular to that of the jet-wave and substantially in the direction of propagation of the jet-wave particles, at said wing, the edge of each wing touching the jet-wave during its passage of the wing.

5. In an electric jet-wave apparatus the combination of means for producing a conductive liquid jet-wave, and two wing shaped electrodes both arranged in a plane substantially perpendicular to the plane of the jet-wave and passing through the position of the jet when currentless, said wing shaped electrodes being placed on opposite sides of the jet-wave and with their edges touching said jet-wave during its passage between the wings.

6. In an electric jet-wave apparatus the combination of means including a magnetic field for producing a conductive liquid jet-wave, and an electrode consisting of a cylinder with a series of sharp circular ribs (a curry-comb-electrode), the cylinder being bent in circular form with a radius equal to the distance from the electrode to the middle point of the said magnetic field, whereas the said ribs are adjusted in the direction of propagation of the jet-wave particles at the particular rib and are adapted to successively touch the jet-wave.

7. In an electric jet-wave apparatus, an electrode comprising two curved cylinders each with a series of sharp circular ribs, said cylinders being arranged on opposite sides of the jet-wave and touching the same.

8. An electric jet-wave commutator, in which the commutated current is conducted

away through two electrodes arranged on opposite sides of the plane of symmetry of the commutator and each comprising a curved rod with a series of sharp circular ribs adjusted in the direction of propagation of the jet-wave particles at the particular rib.

9. An electric jet-wave commutator, in which the commutated current is carried away through two electrodes arranged on opposite sides of the plane in which the jet-wave plays and each comprising a curved rod with a series of sharp circular ribs adjusted in the direction of propagation of the jet-wave particles at the particular rib.

10. In an electric jet-wave apparatus the combination of means including a magnetic field for producing a conductive jet-wave, and an electrode consisting of a curved rod with a series of sharp circular ribs through which the auxiliary current which in co-actuation with the said magnetic field produces the waves on the jet is conducted into the latter.

11. In an electric jet-wave commutator the combination of means for producing a conductive jet-wave, a wing-electrode arranged in the plane of symmetry of the commutator, and two curry-comb-electrodes arranged symmetrically with respect to the said plane, all of which electrodes serve to conduct the commutated current away from the commutator.

12. In an electric jet-wave apparatus the combination of means including a magnetic field for producing a conductive liquid jet-wave, and an electrode member comprising a cylinder with a series of sharp circular ribs (a curry-comb-electrode) the cylinder being bent in circular form with a radius equal to the distance from the electrode member to the middle point of the said magnetic field, whereas the said ribs are adjusted in

the direction of propagation of the jet-wave particles at the particular rib and are adapted to be in constant touch with the jet-wave.

13. For use in electric jet-wave apparatus, an electrode comprising a curved cylindrical rod having a series of sharp circular ribs.

14. In an electric jet-wave apparatus the combination of means including a magnetic field for producing a conductive liquid jet-wave, and two electrode members comprising each a cylinder with a series of sharp circular ribs and arranged on opposite sides of the jet-wave which passes between these electrode members while touching the same, the said cylinders being both bent in circular form with a radius substantially equal to the distance from the particular cylinder to the middle point of the said magnetic field.

15. An electric jet-wave commutator, comprising means including a magnetic field for producing a conductive jet-wave, at least one electrode adapted to be in constant touch with the said jet-wave during its motions, and a double-electrode (main electrode), the two sides of which are adapted to be alternately connected with the first named electrode through said jet-wave, each side of the double-electrode consisting of a cylinder with a series of sharp circular ribs, which cylinder is bent in circular form with a radius equal to the distance from the cylinder to the middle point of the said magnetic field.

16. The electric jet-wave commutator of claim 15, in which the first named electrode comprises two curry-combs of similar nature as the said sides of the double-electrode and arranged adjacent and oppositely to the same.

In testimony whereof I have affixed my signature.

JULIUS FREDERIK GEORG POUL HARTMANN.
